ADJUSTABLE HARD TOP BOAT CANOPY

John P. Barnard, 4600 Holiday Lane, Fort Worth, Tex.

Filed Mar. 21, 1960, Ser. No. 59,795

Term of patent 3½ years

(Cl. D71—1)

FIGURE 1 is a side elevational view of an adjustable hard top boat canopy embodying my new design.

FIGURE 2 is a top plan view thereof.

FIGURE 3 is a bottom plan view thereof.

FIGURE 4 is a front elevational view thereof, and

FIGURE 5 is a rear elevational view.

FIGURE 6 is a cross-sectional view taken transversely across the center of the article as shown in FIGURE 1.

The windshield and fragmentary portion of a boat shown in broken lines in FIGURES 1 and 4 are included for illustrative purposes only.

I claim:

The ornamental design for an adjustable hard top boat

canopy, substantially as shown and described.
